(57) **CLAIM**

The ornamental design for a computer generated image for display panel or screen, as shown and described.

DESCRIPTION

FIG. 1 is a front view of a computer generated image for display panel or screen showing our new design; and

FIG. 2 is an enlarged front view of the first image thereof;

FIG. 3 is an enlarged front view of a second image thereof;

FIG. 4 is an enlarged front view of a third image thereof;

FIG. 5 is an enlarged front view of a fourth image thereof;

FIG. 6 is an enlarged front view of a fifth image thereof;

FIG. 7 is an enlarged front view of a sixth image thereof;

FIG. 8 is an enlarged front view of a seventh image thereof;

FIG. 9 is an enlarged front view of an eighth image thereof;

FIG. 10 is an enlarged front view of a ninth image thereof;

FIG. 11 is an enlarged front view of a tenth image thereof;

FIG. 12 is an enlarged front view of an eleventh image thereof;

FIG. 13 is an enlarged front view of a twelfth image thereof;

FIG. 14 is an enlarged front view of a thirteenth image thereof; and,

FIG. 15 is an enlarged front view of a fourteenth image thereof.

The appearance of the transitional image sequentially transitions between the images shown in FIGS. 1 (or 2) and 3-15. The process or period in which one image transitions to another forms no part of the claimed design. The broken lines shown in FIGS 1-15 are for illustrative purposes only and form no part of the claimed design.
